Primary Examiner — Austin Murphy(74) *Attorney, Agent, or Firm* — Volpe Koenig(57) **CLAIM**

The ornamental design for a display and operating unit, as shown and described.

DESCRIPTION

FIG. 1 is a top, front, left perspective view of a display and operating unit in accordance with my design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a top, front perspective view thereof.

The broken lines represent portions of the display and operating unit that form no part of the claimed design.
